ANTRUM BURR.

Application filed May 9, 1924. Serial No. 711,972.

The present invention relates to surgical instruments and more particularly to an arcuate drill for intranasal aspiration or puncture of the facial sinus or antrum.

5 The facial sinus or antrum of Highmore is a large cavity of somewhat pyramidal form located within the superior maxillary bone. It is subject to numerous surgical diseases, the most common being infection 10 followed by suppuration, necessitating drainage. The walls of the antrum are comparatively thin, particularly that portion of the internal wall which separates the antrum from the inferior meatus of the 15 nasal fossa. The extreme thinness of the internal wall and its accessibility through the nares renders the intranasal route desirable for surgical operation. However, due to lack of facilities and suitable instruments for puncturing the internal antrum wall, surgical preference has been given to operations by the dental route, 20 which necessitates the sacrifice and extraction of a molar tooth, and drilling through 25 the alveolar process, or to enter the antrum through the lower exterior wall, just above the apices of the tooth roots. The sole means of intranasal operations has been by 30 use of a trocar or cannula, with which the antrum wall is punctured by application of pressure. The tortuous passage through the 35 nasal fossa does not readily accommodate a straight trocar. A curved trocar or cannula is unsuitable since direct driving pressure is necessary and more or less twisting or 40 boring movement is required to penetrate the antrum wall. In such method there is no way of controlling the extent of the bone breakage, and the wall may be fractured or splintered through a greater area than intended. 45 In case the access opening thus formed is too small, the use of the trocar must be followed by that of a rasp.

In the present invention means is contemplated for entering the antrum through the nasal route by drilling through the wall between the antrum and the inferior meatus. Since this point of operation cannot be approached directly, or in a straight line 50 through the nares, there is employed an instrument having an arcuate or curvilinear shaft provided with a burr at its extremity operated by a flexible drive shaft extending through the hollow curvilinear stem. To

prevent the disconnection and loss of the 55 burr or drilling implement while in operation, a form of split bushing is provided at the extremity of the curvilinear stem, in which the burr or drill is mounted, such bushing being arranged to lock the burr or 60 drill head against detachment while permitting its free rotation. The initial drive shaft operated by any suitable motor or source of power is interconnected with the flexible 65 shaft by friction drive mechanism, located within the hollow handle of the instrument.

The object of the invention is to provide a simple but efficient means for entering the maxillary antrum by means of a cutting or 70 drilling instrument, which will afford a clean cut orifice, without fracture or splintering of the antrum wall.

A further object of the invention is to provide a bone drill or the like, the parts 75 of which are easily and readily accessible for sterilization, but which are so interengaged and assembled as to prevent their disconnection and loss while in use, and which will moreover be protected against breakage by frictional drive means, yieldable whenever abnormal resistance to the drill is encountered.

A further object of the invention is to provide an instrument of convenient shape and curvature to accommodate it readily to various sizes of nares and by which danger of fracture of the lateral wall of the nose is obviated, which sometimes occurs, incident to the necessary exertion of pressure on an 85 antrum trocar.

While the present instrument is especially designed and adapted for nasal operations, it is also applicable for drilling arcuate passages as for instance in splicing bone fractures. By employing an instrument having 95 stem and burr of proper size, curved passages may be drilled from one side of a bone fracture to the other to permit the passage of sutures.

With the above primary and other incidental objects in view as will more fully appear in the specification, the invention consists of the features of construction, the parts and combinations thereof, and the mode of operation or their equivalents as 100 hereinafter described and set forth in the claims.

Referring to the drawings, Fig. 1 is a lon-

litudinal sectional view of the surgical instrument forming the subject matter hereof. Fig. 2 is an enlarged sectional view of the detachable mounting for the burr. Fig. 3 is a modification of the burr mounting and driving connection. Fig. 4 is a detail view of the split bushing by which the burr is detachably secured to the end of the hollow stem. Fig. 5 is a detail view of the friction clutch disc for the driving connection. Fig. 6 illustrates a modified form of burr, particularly adapted for drilling curvilinear passages through bone structure for the introduction of splicing sutures and tenons. Fig. 7 is a diagrammatic transverse vertical section of the nasal fossæ, in a plane anterior to the superior turbinate bone, showing the relation and approximate size of the antrum, and having indicated thereon, the various routes of entrance. Fig. 8 is a diagrammatic view of a fractured bone splicing operation.

Like parts are indicated by similar characters of reference throughout the several views.

The instrument has been illustrated in the drawing, very much enlarged. It will be understood that the length and diameter of the curvilinear stem and size of burr will be appropriate to the size of the parts operated upon.

Referring to the drawings, 1 is a hollow handle, within which is contained the frictional driving connection for the burr or drill. Detachably secured at the extremity of the handle 1, by means of chuck jaws 2 is a curvilinear hollow stem 3. The chuck jaws 2 may be of any suitable form or construction. In the present instance, they consist of a tapered sleeve, carried by the handle section 1, and surrounding the end of the curvilinear stem 3. The jaws 2 are contracted by a tapered collar 4 screw threaded upon the handle section 1. The particular mode of attachment is immaterial and obviously other forms of attaching means may be substituted. On its outer extremity the curvilinear hollow stem 3 carries the drill or burr 5. Such burrs are made in various shapes and styles, that shown for illustrative purposes being a spherical burr. The burr 5 is revolvably mounted in a split bushing 6, screw threaded in the end of the curvilinear stem 3. To prevent the accidental disengagement of the burr, the shank 7 of the burr is provided at its inner end with a head or shoulder 8, which prevents its withdrawal axially from the bushing 6. The shank 7 is positioned intermediate the two halves of the split bushing 6, as shown in detail in Fig. 4. The bushing is then screwed into the end of the hollow stem as shown in Figs. 1, 2 and 3. Obviously, when so positioned the burr cannot become dislodged or accidentally disconnected and lost in the antrum

cavity or in the nasal fossæ. Secured to the shank 7, of the burr or drill, preferably permanently by brazing, welding or otherwise, is a flexible drive shaft 9. This drive shaft 9 may be a small helically wound wire or spring, as is sometimes employed, or it may consist in a chain comprising a succession of interpivoted links. However, in practice a section of wrapped or covered piano string has been found to operate satisfactorily. Numerous forms of flexible shafts are obtainable, any of which if of sufficiently small diameter may be employed. At its inner end, the flexible shaft 9 is connected to a shank or stud 10, of polygonal cross section, preferably square. This shank or stem 10 is loosely received in a corresponding socket in the end of the drive shaft 11. The drive shaft 11 extends axially within the handle section 1, and is provided with a bearing in a lug 12, in one end of such handle mounting, and has loose journal bearings in the inner end of the chuck sleeve 2 at the opposite end of the handle section. Fixedly secured to the drive shaft 11 is a friction drive collar 13, adjacent to which are loosely journaled upon the drive shaft two driving gears 14, spaced apart and between which is interposed a friction drive disc 15. The disc 15 is keyed upon the shaft 11 for unison rotation therewith and is free for axial adjustment. Bearing upon the gears 14 on the side opposite the fixed collar 13 is a second friction collar 16, also keyed upon the drive shaft 11 for unison rotation, but slidably adjustable in an axial direction and exerting pressure upon the gears 14 under the influence of the spring 17. The spring 17 is of helical formation, bearing at one end upon the sliding friction collar 16 and abutting at its opposite ends upon a stop nut 18, adjustable upon the shaft 11, to vary the friction of the spring and secured in its adjusted position by means of the lock nut 19. The construction is such that while the gears 14 are loosely journaled upon the shaft 11 for independent rotation, they are clamped between the friction collars 13 and 16 and the interposed friction disc 15 under spring pressure of sufficient tension to afford the necessary driving power. The gears 14 intermesh with a driving gear pinion 20 on a countershaft 21, suitably journaled in the handle section 1, in parallel relation with the main drive shaft 11, and extending beyond the handle section where it is connected to a driving motor, or other suitable source of power. The frictional engagement of the collars 13, 15 and 16 with the driving gears 14 is sufficient to drive the shaft 11 and with it the burr or drill 5 in any ordinary operation. However, should the resistance to the burr or drill become sufficiently great to endanger either the patient or the instrument, or be such as to be likely to cause breakage

of the burr, the frictional driving engagement between the collars and the gears will be overcome and more or less slippage will occur.

5 By disengaging the chuck collet 4, the curvilinear tubular stem 3 may be disengaged from the handle and with it the flexible shaft 9, the shank 10 of which loosely engages in a corresponding socket in the 10 end of the shaft 11. By unscrewing the bushing 6, the burr 5 may be disengaged and the shaft 9 withdrawn from the tubular stem, permitting complete sterilization of the operative parts. Inasmuch as the head 15 8 upon the shank 7 of the burr prevents its accidental withdrawal and permits its disengagement only by the unscrewing of the bushing 6 and the fact that the burr is frictionally driven, the connection or clutch 20 being such as to yield to undue resistance, the burr is fully protected against breakage, and loss, while in use.

It may be desirable for some conditions of use, or to meet requirements of the different 25 practitioners to provide for the disengagement of the burr from the flexible drive shaft 9, which as before mentioned, is shown in Figs. 1 and 2 as permanently secured to the burr. This construction is 30 shown in Fig. 3, wherein the flexible shaft 9 is provided with a head 23, having therein a socket to receive a squared stud 22 on the end of the shank 7 of the burr. The construction is otherwise as before described. This 35 construction shown in Fig. 3 enables the burr to be replaced without the necessity of replacing the entire flexible drive shaft 9. Inasmuch as burrs of different sizes, shapes and character will be used with the same handle and 40 curvilinear stem, the construction shown in Fig. 3 will be quite convenient for such replacement or interchange of burrs.

In Fig. 7 there is shown a burr or drill head of somewhat different shape, particularly 45 applicable to the drilling of curved passageways to facilitate the wiring or interconnection of fractured bones. Inasmuch as such points of operation are more readily accessible, there is less danger of losing the burr in the opening. It is also desirable that 50 the arcuate stem 3 be of smaller diameter than the burr, in order that the burr may clear itself of bone chips. The burr illustrated is of mushroom shape or conoidal 55 form with the base of the conoidal burr head overhanging the periphery of the stem. Because of the small diameter of the stem and since it is unnecessary to protect the instrument against accidental disengagement or 60 loss of the burr, in such bone drilling operations, the shank 7' of the burr is preferably journaled directly in the end of the stem 3. This 65 enables a bearing of larger size and greater strength. Otherwise, the construction and operation is as before described.

In Fig. 8, there is illustrated the application of the instrument to such broken bone splicing operation. In splicing fractures, it is quite the practice at the present time to drill holes in the adjacent ends of the broken 70 bone through which wires are strung or even nails or screws are sometimes used for this purpose. However, such holes heretofore, have necessarily been straight, and have usually been passed diagonally from one side 75 to the other of the bone and across the fracture. The present instrument enables such holes to be drilled through a curvilinear path, entering the bone and coming out again on the same side of the bone, but on 80 opposite sides of the point of fracture. This operation is somewhat like a stitch in sewing, the wire or suture being passed through the hole thus formed.

In the diagrammatic view Fig. 7, the application of the present instrument to antral purposes is shown in dotted lines. By its use 85 the entrance orifice may be made approximately at the bottom of the nasal fossae and somewhat lower than when using a nasal trocar. The antral burr described will cut its 90 way through the wall quickly and with minimum pain. By lateral motion the initial opening may be enlarged and extended as low as desired. If the bone is dense or hard, 95 there is no danger of fracture as sometimes occurs under the heavy pressure required to force a trocar through the wall. Moreover, the use of a rasp for enlargement of the 100 opening is eliminated. In Fig. 7 the other 100 external routes at present employed are indicated by the darts 24 and 25 respectively. Obviously the route 24 necessitates the sacrifice of a molar tooth.

It is obvious that the instrument herein 105 shown and described may be applied to many other bone drilling operations as will readily occur to the skilled surgeon. For different purposes, the stem carrying the burr may be made of various degrees of curvature and 110 of greater or less length. To meet unexpected or unusual conditions or emergency operation, the tubular stem may be made of material capable of being flexed or bent into various shapes at the time of use to enable 115 operation in otherwise inaccessible locations. The flexible drive connection enables the operation of the burr through various irregular shapes into which the stem might be bent. The instrument is adaptable to dental drilling 120 operations and oral surgery, for which purposes a variety of interchangeable tubular stems of different extent and curvature would be provided. The advantage of the instrument for intranasal operations is illustrated in Fig. 7, wherein the thicker portion 125 of the internal wall of the antrum is shown being penetrated at a much lower level than is possible with the use of a nasal trocar. In using the trocar the surgeon 130

necessarily selects the higher and thinner wall area 24, as the point of entrance, with sacrifice of drainage facilities, because of its accessibility and the impossibility of forcing the trocar through the thick lower wall.

From the above description it will be apparent that there is thus provided a device of the character described possessing the particular features of advantages before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect, and the invention is, therefore, claimed in any of its forms or modifications within the legitimate and valid scope of the appended claims.

Having thus described our invention, we claim:

30 1. In a surgical drill, a hollow handle portion, an inflexible arcuate tubular stem carried thereby, a burr revolvably mounted at the extremity of the arcuate stem, said arcuate stem being shaped and proportioned to follow the burr through a restricted passage, a flexible shaft extending through the stem and operatively connected with the revolvble burr, and driving means for rotating the shaft located within the hollow handle portion, with which the flexible drive shaft is operatively connected.

45 2. In a surgical drill, a hollow mounting, driving mechanism enclosed therein, an inflexible cannula carried thereby, such cannula being proportioned and shaped for introduction through the nares into the antrum, a revoluble drill burr mounted at the extremity of the cannula and a driving connection extending through the cannula and operatively connecting the burr with the driving mechanism in the mounting.

55 3. In a surgical drill, means for operating a drill burr through a curvilinear passage including a handle portion, a curvilinear mounting for the drill burr shaped and proportioned for introduction through the nares into the antrum, a drill burr revolvably mounted at one end thereof, the opposite end of said mounting being connected to said handle portion and a flexible drive shaft operatively connected with the burr for rotating the burr during its advance through such curvilinear path.

60 4. In a surgical drill, a revolvble burr, a flexible shaft operatively connected with the

burr, and means following in the path of the burr for guiding the burr through a curvilinear path of travel simultaneously with its rotation.

5. In a surgical drill mounting, a revolvble burr, an inflexible tubular stem of segmental arcuate form at one end of which the burr is revolvably mounted the other end of which is connected to said handle portion, said stem being shaped and proportioned to enter any passage traversed by said burr, a drive shaft extending through the tubular stem, and safety means for preventing the accidental detachment of the burr from the stem while permitting its free rotation.

6. In a drill, a revolvble burr, a tubular stem at one end of which the burr is revolvably mounted, a drive shaft extending through the tubular stem, and a split bearing for said burr engaged with the tubular stem, the burr being shouldered on opposite sides of the split bearing to prevent its withdrawal.

7. In a drill of the character described, a revolvble burr, a tubular stem upon the end of which the burr is mounted, a drive shaft extending through the stem, and operatively connected with the burr, a split sleeve screw threaded in the extremity of the hollow stem and forming a bearing for the burr, and spaced shoulders upon the burr coincident with the opposite ends of the split sleeve for preventing the withdrawal of the burr from the sleeve while the latter is held in assembled relation by its engagement within the hollow stem.

8. As an article of manufacture, a unitary structure comprising a drill burr, a trunnion integral with said burr, a flexible drive shaft fixedly attached at one end to the burr, and a shank attached to the opposite end of the shaft for engagement with a driving member.

9. As an article of manufacture, a drill burr including a shank having therein a peripheral groove forming a trunnion upon which the burr rotates and spaced shoulders defining said peripheral groove.

10. In a drill of the character described, a tubular stem shaped and proportioned for introduction into a restricted passage, a burr revolvably mounted at the end of the stem in such position and of such size as to clear a passage for the advancement of the stem, and having an integral bearing shank, a journal bearing at the end of the stem in which the shank rotates removable from the stem with said burr and preventing accidental disengagement of the burr from the stem while within the passage, a peripheral shoulder upon the burr shank preventing axial withdrawal of the shank from its bearing, and a drive shaft for the burr extending through the tubular stem.

11. In a drill of the character described, a hollow handle portion, a main drive shaft

revolvably mounted therein, a frictional drive connection for said shaft, a tubular stem carried by the handle portion, a drill burr revolvably mounted at the extremity of the 5 tubular stem, and a supplemental drive shaft extending through the tubular stem and operatively connecting the burr and main drive shaft.

12. In a drill of the character described, 10 a hollow handle portion, a main drive shaft revolvably mounted therein, a frictional drive connection for said shaft, an arcuate tubular stem carried by the handle portion, a drill burr revolvably mounted at the extremity 15 of the tubular stem, and a flexible drive shaft extending through the tubular stem and operatively connecting the burr and main drive shaft.

13. In a surgical drill of the character described, 20 a hollow handle portion, a revolvable main drive shaft mounted therein, a chuck at one end of the handle, a hollow bent stem shaped and proportioned for introduction through the nares into the antrum detachably engageable by said chuck, a drill burr 25 detachably mounted at the extremity of the tubular stem, said stem being shaped and proportioned to enter the passage traversed by said burr, and a supplemental drive shaft 30 detachably connecting the burr with the main drive shaft.

14. In a surgical drill of the character described, 35 a hollow handle portion, a revolvable main drive shaft mounted therein, a chuck at one end of the handle, an inflexible tubular curvilinear stem of segmental arcuate formation detachably engaged by said chuck, a drill burr revolvably mounted at the extremity 40 of the stem and guided thereby through a curvilinear path of travel, said stem being shaped and proportioned to enter the passage traversed by said burr, and a flexible drive shaft extending through the

curvilinear stem and detachably connecting the burr with the main drive shaft. 45

15. In a drill of the character described, a revolvable burr, a mounting therefor, a drive shaft operatively connected with the burr, a drive gear loosely journaled upon the drive shaft, a pair of spaced collars one of which is fixedly secured upon the drive shaft, the other of which is axially adjustable thereon but engaged therewith for unison rotation, and between which the gear is mounted, and a spring urging the movable collar toward the fixed collar to yieldingly clamp the drive gear therebetween. 50

16. In a drill of the character described, a revolvable burr, a mounting therefor, a drive shaft operatively connected with the burr, a countershaft, intermeshing gears operatively connecting the drive shaft and countershaft one with the other, one of said gears being loosely mounted upon its shaft, and friction discs on opposite sides of the 55 loosely mounted gear, mounted for rotation with the shaft and yieldingly engaging the shaft under spring pressure. 60

17. In a drill of the character described, 70 a hollow handle section, an arcuate tubular stem detachably connected with the hollow handle section, a revolvable burr detachably mounted at the extremity of the tubular stem, a main drive shaft mounted in the hollow handle section, a flexible shaft detachably connecting the revolvable burr with the main drive shaft, and a frictional drive clutch transmitting power to the main drive shaft and adapted to yield under undue resistance to the rotation of the burr. 75

In testimony whereof, we have hereunto set our hands this 5th day of April, A. D. 1924.

ROY S. BINKLEY.
